FREQUENCY SHIFT PULSE TIME
MODULATION

Clarence H. McShan, Newark, N. J.

Application January 17, 1947, Serial No. 722,579

15 Claims. (Cl. 179—171.5)

1 The present invention relates to modulation systems for use with radio frequency carrier signals, and more particularly to new and improved pulse time modulation systems which are simple in construction and highly effective in operation.

Modulation systems have been devised that are characterized by low noise background reception. Examples of such systems are the commonly known forms of frequency modulation, including the Armstrong phaseshift method, the center frequency control system using a reaction tube and variable oscillator, and, more recently, the piastron method, which is an improvement over the phaseshift method. It has also been proposed to generate pulses, the pulse width being a function of the amplitude of a modulating signal, and to use the width modulated pulses to modulate a conventional frequency modulated transmitter. While such systems have been used effectively, they are relatively complex and are not particularly suitable for use in low cost crystal controlled transmitters where minimum space requirements and low power consumption are of prime importance.

The principal object of the present invention, accordingly, is to provide new and improved pulse time modulation systems which are free from the above noted defects of the prior art, and are simple in construction and highly effective in operation.

A further object of the invention is to produce new and improved pulse time modulation systems of the above character which provide signals that may be received with conventional frequency modulation receiving equipment using a discriminator and a limiter, for example.

Still another object of the invention is to provide new and improved pulse time modulation systems of the above character which provide low noise background reception and embody relatively simple circuits possessing excellent stability.

Another object of the invention is to provide a combined pulse time modulated and pulse frequency modulated system which affords at least two transmission channels with a minimum of equipment and with highly satisfactory operating characteristics.

The objects of the invention are attained by providing a pulse time modulation system in which radio frequency carrier pulses of different frequencies are alternately transmitted in such fashion that substantially no time delay exists between successive pulses of different frequencies. The pulse widths of each consecutive pair of carrier pulses of different frequencies are modu-

lated in accordance with the amplitude of a modulating signal in complementary fashion such that a decrease in the width of one pulse of one frequency is accompanied by an increase in the width of the next pulse of different frequency, while the total pulse width for any two consecutive pulses is maintained substantially constant. The relation between the width of each pulse and the instantaneous modulation amplitude of the intelligence which is to be transmitted by the modulation system is preferably made substantially linear.

In one embodiment of the invention, a pair of crystal oscillators of different frequencies provide outputs to a single resonant circuit capable of transmitting both frequencies. The outputs from the two crystal oscillators are controlled by any suitable pulsing means such as a multivibrator, for example, such that the outputs of the two crystal oscillators are alternately supplied to the resonant circuit. The multivibrator is controlled by the modulation that is to be transmitted in such fashion that the pulse widths of successive half-cycles of the multivibrator output are modulated linearly with respect to the modulation input.

In accordance with another embodiment of the invention, a variable oscillator is adapted to lock in alternately with the two crystal oscillators of different frequencies. The locking-in of the variable oscillator may be controlled in any suitable manner as by means of a reactance tube, for example, pulse time modulated by means of a multivibrator in the manner outlined above, or by other suitable means.

Instead of using a variable reactance tube to control a variable oscillator, pulses from the multivibrator or other like means may be used to control the alternate insertion and removal of additional reactance in the oscillator tank circuit, to produce alternate carrier pulses of different frequencies in accordance with the invention. Modulation of the lock-in oscillator frequency by the suppressed frequency (the frequency not being transmitted at the moment) may be eliminated by limiting the lock-in oscillator output by any one of several well known means.

The invention also contemplates modulating the repetition rate of the control pulses in accordance with a modulating signal. With this construction, two transmission channels are provided; one using pulse time modulation and the other using frequency modulation of the conventional type.

It will be apparent from the foregoing that the novel pulse time modulation system of the present invention affords essentially the same advantages as conventional frequency modulation equipment with less equipment and with relatively simple circuits possessing excellent stability. Further, it enables the use of oscillators which may employ crystal control. In addition, the pulse time modulated signals that are produced are capable of being received on standard frequency modulation receivers now in general use, and the system is characterized by low noise background reception.

Additional objects and advantages of the invention will be apparent from the following detailed description of several representative embodiments, taken in conjunction with the accompanying drawings in which:

Figure 1 is a schematic diagram of a pulse time modulation system constructed according to the present invention;

Figure 2 is a modification of the modulation system shown in Figure 1 in which a variable oscillator is employed which is adapted to lock in with either of two oscillators operating on different frequencies;

Figure 3 is a schematic diagram of another embodiment of the invention in which modulation of the pulse time is produced by controlling the insertion and removal of an additional reactance in a tank circuit;

Figure 4 illustrates a further embodiment of the invention utilizing rectifying means; and

Figure 5 is a schematic diagram of still another embodiment of the invention which affords two separate and independent transmission channels.

In the system shown in Figure 1 of the drawings, two radio frequency signals are provided by the crystal controlled oscillators 10 and 11, for example, whose frequencies are f_1 and f_2 , respectively. The outputs of the oscillators 10 and 11 are supplied to the grids of a pair of electronic tubes 12 and 13, respectively, which may be of any suitable type containing at least three elements (grid, plate and filament). The outputs of each of the tubes 12 and 13, respectively, are supplied to a common resonant circuit 14 whose band width is made sufficiently wide to pass signals of the two frequencies f_1 and f_2 . Signals of frequencies f_1 and f_2 are alternately fed to the resonant circuit 14 in any suitable manner, as by alternately blocking the tubes 12 and 13, for example.

Blocking of the tubes 12 and 13 is preferably accomplished by alternately driving their cathodes positive with respect to their grids until plate current ceases to flow. The blocking voltages for the tubes 12 and 13 may be supplied from a conventional type multivibrator 15, for example. The multivibrator 15 may be of the usual type whose basic principle of operation is known to those skilled in the art, and it will not be described in detail herein. The biasing voltage pulses from the multivibrator 15 are taken off at the cathode coupling resistors 16 and 17, respectively, as shown in Figure 1.

The modulation voltage representing the intelligence to be transmitted is impressed upon the input terminals 18 of a transformer 19, the secondary winding 20 of which has a center tap 21. The center tap 21 is connected to the positive terminal of a conventional plate supply (not shown) and through the plate resistors 22 and 23 to the plates 24 and 25 of a conventional double

triode tube 26. The terminals 27 and 28 of the secondary winding 20 of the transformer 19 are connected through the resistors 29 and 30, respectively, to the control grids 31 and 32, respectively, of the tube 26. A condenser 33 is connected to the plate 25 and grid 31 of the tube 26, and a condenser 34 is connected to the plate 24 and the grid 32 of the tube 26.

With this construction, the modulation voltage applied to the multivibrator 15 is in series with the grid return to the positive terminal of the plate supply and is 180° out of phase in each leg of the multivibrator. Hence, the condensers 33 and 34, respectively, will have their voltage decay times alternately increased or decreased, thereby increasing or decreasing the holding or conducting time of the respective triodes in the multivibrator tube 26, depending upon the polarity of the modulating voltage. This effectively gives a time modulated pulse voltage which is used to transmit alternately the two radio frequency signals f_1 and f_2 from the oscillators 10 and 11, respectively, as will be described in greater detail hereinafter.

Preferably, the relation between the pulse time of the pulses supplied by the multivibrator 15 and the instantaneous modulation amplitude of the voltage representing the intelligence to be transmitted should be made substantially linear by operating the condensers 33 and 34 of the multivibrator 15 on a small portion of the condenser discharge characteristic curve. This may be accomplished, for example, by supplying a positive voltage to the grid return at the center tap 21 of the transformer secondary 20, whose value is at least equal to the plate voltage supplied to the tubes in the multivibrator 15.

When the modulating signal applied to the multivibrator 15 is zero, pulses of frequencies f_1 and f_2 will be alternately transmitted from the output of the resonant circuit 14, the duration of each pulse being approximately half the total duration for the two pulses under optimum conditions. With proper adjustment, the pulse frequency f_c will remain substantially constant and it should preferably be made about three times the highest audio frequency in the intelligence which is to be transmitted.

Generally speaking, the pulse frequency f_c should be made very much smaller than either of the radio frequencies, f_1 or f_2 . Accordingly, low-pass filters 35 and 36 may be used between the cathode resistors 16 and 17, respectively, of the multivibrator 15 and the blocking stages comprising the tubes 12 and 13, respectively. Preferably, the upper cut-off frequency for the low-pass filters should be at least ten times the pulse frequency f_c in order to insure that the output pulses will have good, square wave form. The purpose of the filters 35 and 36 is to prevent signals of frequencies f_1 or f_2 from entering the circuit of the multivibrator 15. They also tend to reduce degeneration in the blocking stages comprising tubes 12 and 13, respectively, during their conducting times.

Carrier signals, pulse time modulated in the manner described above may be received with a conventional type frequency modulation receiver using a discriminator and limiter, the operation of which elements is well known in the art. By tuning the receiver to locate signals of frequencies f_1 and f_2 above and below the resonant frequency of the discriminator, respectively, alternate pulses of frequencies f_1 and f_2 will produce pulses of alternate polarity in the output of the discrimi-

nator. When these time modulated pulses are passed through a low-pass filter, they are converted back to substantially the original modulating voltage. A low-pass filter exists in most frequency modulation receivers for the deemphasis of the high frequencies and it may be used satisfactorily for this purpose. Better results may be obtained if a filter having a sharp cut-off at the highest desired frequency is used, thus preventing the frequencies near the high end of the spectrum from being attenuated, as occurs with the conventional R. C. filter used for deemphasis purposes in standard frequency modulated receivers.

Since pulses of frequencies f_1 and f_2 follow each other immediately, the result is a substantially constant transmission, which prevents the occurrence of dead spots through which noise can enter the receiver. When either pulses of frequencies f_1 or f_2 are completely cut off, the threshold of improvement is lessened, or, the necessary signal strength to over-ride the noise is considerably increased. In addition, the volume of the demodulated signal for a given limiter level is approximately half that obtained with both pulses. Therefore, the use of two crystal controlled oscillators 10 and 11 to obtain a continuous transmission is justified, especially when considerable power is used, as the increase in all-around efficiency of transmission and reception obviously offsets the additional cost of a low-power crystal oscillator and blocking circuit.

The Federal Communications Commission defines the carrier frequency f_0 of an FM system as being the mean or average frequency transmitted. For this system,

$$f_0 = \frac{f_1 + f_2}{2}$$

Also, their regulations set the maximum band width at 150 kc. or ± 75 kc., either side of the carrier frequency, f_0 , so that the maximum difference frequency

$$\Delta f = f_1 - f_2$$

between the two oscillators must not exceed 150 kc.

Tests of the novel pulse time modulation system comprising the present invention have been made using a carrier average frequency f_0 of 4.3 mc. in order to feed the signal directly into a standard 4.3 mc. I. F. amplifier with the usual limiter and discriminator. The effective band width of the receiver was approximately 200 kc. The multivibrator frequency, f_c was set at 15 kc. The two oscillators were set at ± 75 kc. of 4.3 mc. Observation of the discriminator output on the oscilloscope to determine the frequency response and wave form showed substantially constant output between 90 and 5,000 C. P. S. with less than 5% distortion.

In the modification shown in Figure 2 of the drawings, the outputs of the two oscillators 10 and 11 of frequency f_1 and f_2 , respectively, are coupled loosely into the tank circuit of a variable oscillator 37. The oscillator 37 is adapted to be controlled by means of a conventional type reactance tube 38 in such fashion as to lock-in alternately with one or the other of the two crystal controlled oscillators 10 or 11 when the reactance tube 38 is pulsed by the pulse time modulated multivibrator 15.

A further modification of the system shown in Figure 2 is illustrated in Figure 3 in which the resonant frequency of the tank circuit 39 is

adapted to be changed by means of a by-pass or blocking condenser 40, a crystal rectifier 41, and a variable condenser 42, all connected in series and in parallel with the tank circuit 39 of the variable oscillator 37. The chokes 43 and 44 serve to isolate the radio frequency from the circuit of the multivibrator 15.

As pulses are received from the multivibrator 15, the voltage across the diode 41 will be alternated in polarity and will preferably be at least equal to the peak R. F. frequency voltage impressed on the diode 41 from the tank circuit 39 when in operation. When the diode 41 is conducting, its impedance may be about 30 ohms, for example, and it effectively connects the condensers 40 and 42 in series across the tank circuit 39 of the oscillator 37. When the diode 41 is not conducting, its impedance is very high so that it has relatively little effect upon the tank circuit 39. In a typical circuit, the capacitance between the elements of the diode 28 may be approximately two micro-microfarads. A frequency of 3000 mc. must be reached before the capacitive reactance equals 30 ohms, so that a substantial change in frequency may be had for much lower frequencies, where this circuit will generally be used.

The circuit shown in Figure 3 is independent of voltages insofar as frequency is concerned, which is an advantage over the reactance tube used in the embodiment illustrated in Figure 2, and, in addition, requires fewer components. It will be understood that this circuit may be used in a wide variety of applications for changing the impedance in any circuit by means of a reversal of a D. C. voltage.

Figure 4 illustrates still another embodiment of the invention in which rectifying means controlled by the multivibrator 15 are employed for impressing the outputs of the oscillators 10 and 11 selectively upon a tank circuit 45. In this embodiment, a pair of rectifiers such as, for example, the diodes 46 and 47, respectively, are alternately biased by the pulse modulated voltage entering the conductors 48 and 49 in such a manner as to render one conducting and to bias the other substantially below cutoff. The condensers 50 and 51 serve to block off the passage of D. C. to the crystal oscillators 10 and 11, respectively, and the chokes 52 and 53 are employed to decouple the radio frequency from the common connecting lead 48, which is by-passed to ground by the condenser 52a.

Any capacitive coupling existing across the diodes 46 and 47 may be neutralized in any suitable manner. The output may be taken off in any convenient fashion, such as, for example, by means of a coupling coil 55. The condenser 54 serves to by-pass the tank circuit 45 to ground, as shown in Figure 4. The by-pass condensers 52a and 54 should preferably be made small enough to allow the time modulated pulses from the multivibrator 15 to pass with little distortion, while effectively by-passing the two radio frequency signals f_1 and f_2 to ground.

Pulse width modulation has the advantage of not being affected by non-linear distortion in the transmission path. Moreover, constant amplitude pulse modulation is the only type that can be applied in the case of certain types of VHF generators. For example, two magnetrons, each designed to operate at different frequencies, may be alternately pulsed by means of pulse width modulation to obtain higher power transmission in the VHF range.

In the system described above, a symmetrically modulated multivibrator circuit has been used for the purpose of maintaining a substantially constant vibrator frequency. With this construction, a pulse center is furnished which is constant in time repetition and whose sides vary in accordance with the modulation voltage. It will be understood that one side only may be made to vary in time, in which case the front edge of the pulse will be held stationary with respect to time. This form of pulse modulation is desirable when the multivibrator frequency is synchronized with a stabilizing frequency.

In the embodiment illustrated in Figure 5 of the drawings, a system is illustrated by means of which both pulse time modulated and frequency modulated signals may be transmitted. Referring to Figure 5, the multivibrator 15 is the same as in Figure 1 except that a second modulating transformer 56 is inserted between the mid tap 21 and the resistors 22 and 23. In this case, one modulating signal is supplied to the terminals 18 of the transformer 19, while a second modulating signal is supplied to the input terminals 57 of the transformer 56.

It has been found that the modulating voltage input supplied to the transformer 56 will vary the frequency rate of the multivibrator 15 without materially upsetting the pulse time ratio as governed by the channel through the transformer 19. The channel through the transformer 19, on the other hand, does not materially alter the pulse frequency in comparison with that obtained by the channel through the transformer 56, so that two separate and independent channels of communication are produced which are characterized by a minimum of cross-talk.

The output of the system shown in Figure 5, comprising the pulse time modulated signal and the pulse frequency modulated signal, may be received by a conventional type frequency modulation receiver. The frequency modulated signal can be readily demodulated since the regular pulse time modulation as supplied at the discriminator and low-pass filter output of the receiver appears to be substantially free from the effects of pulse frequency modulation. By adding a second discriminator to take the multivibrator frequency f_c from the regular discriminator of the receiver, a second channel is provided whose response is substantially independent of the pulse time modulation.

This is true because pulse time modulation is, in effect, a form of phase modulation, the phase shift being substantially smaller than the frequency shift provided in the second channel, while, on the other hand, frequency modulation of the pulse rate is practically non-responsive to the first discriminator output due to the integrating effect of the low-pass filter in the output of the receiver. With proper design proportions, cross-talk may be held low enough not to be objectionable for telephone and similar services. It is also possible that cross-talk between channels may be balanced out with suitable networks in the audio circuit. The second frequency modulated channel enhances the general value of the system according to the invention with very little additional equipment.

In general, about 80% modulation of the pulse width is practical in pulse time modulation systems constructed according to the present invention, the limitation being the shortest pulse that can be transmitted on a given band width while

retaining a rectangular shape. It can be shown that the general requirement for band width is:

$$\text{Band width} = 10f_c + \Delta f = 30f_a + \Delta f$$

where f_c is the pulse rate, f_a is the highest audio frequency to be transmitted, and Δf is the frequency separation of the two R. F. carriers of frequencies f_1 and f_2 . It is assumed here that $f_c = 3f_a$ for reasonably low distortion. This equation gives an approximate and conservative value of the band width required.

It will be understood that the several circuits described in detail above are intended merely to be illustrative of the invention and are capable of modification in a number of respects within the scope of the invention. For example, any other suitable pulse generating device may be used instead of the multivibrator shown. In fact, any device capable of pulsing two frequencies alternately while maintaining the total period substantially constant, and varying the time relationship of pulses of frequencies f_1 and f_2 in accordance with the amplitude of the modulation voltage, is capable of providing frequency shift pulse time modulation. Harmonic generators are occasionally used in transmitters employed for pulse time modulation, in which case the blocking stage may be used advantageously as a harmonic generator, provided that it comprises at least a triode.

It will be further understood that conventional means may be employed in the foregoing systems to isolate the oscillator from the blocking tube to prevent adverse reaction on the oscillator stability. Additional isolation stages may be inserted, and other refinements common to the art may be made within the scope of the invention.

The novel modulating systems disclosed herein have wide application in the electronic art. For example, they may be effectively used as audio or video channels, automatic volume controls, ringing circuits, synchronizing channels, control channels, automatic tone controls, and two dimensional sound systems. Other applications will be apparent to those skilled in the art.

While several representative embodiments have been described in detail herein, the invention is not to be limited thereto, but is susceptible of numerous changes in form and detail within the scope of the appended claims.

I claim:

1. In a radio frequency system, the steps of alternately producing radio frequency carrier signals of two different frequencies in the form of consecutive pulses of given time duration, and modulating said carrier pulses in accordance with a modulating signal.
2. In a radio frequency system, the steps of alternately producing radio frequency carrier signals of two different frequencies in the form of consecutive pulses of given time duration, and modulating the time durations of the alternate pulses in accordance with a modulating signal while maintaining the total time duration of each consecutive pair of pulses substantially constant.
3. In a radio frequency system, the steps of alternately producing radio frequency carrier pulses of two different frequencies, modulating the frequency of said carrier pulses in accordance with one modulating signal while maintaining a substantially constant pulse time proportion between each consecutive pair of pulses, and modulating the widths of the alternate pulses in

accordance with another modulating signal while maintaining a substantially constant pulse frequency.

4. In a radio frequency system, the steps of alternately producing radio frequency carrier pulses of two different frequencies, modulating the widths of the alternate pulses in accordance with the amplitude of a modulating signal, such that opposite, complementary changes in pulse width are produced in each consecutive pair of pulses, whereby the total pulse width for each consecutive pair of pulses is maintained substantially constant, and transmitting said modulated pulses.

5. In a radio frequency system, the steps of generating two radio frequency signals of different frequencies, alternately blocking said two radio frequency signals in such fashion as to produce alternate radio frequency carrier pulses of said different frequencies, modulating the duration of said alternate pulses in accordance with the amplitude of a modulating signal while maintaining the total duration of each consecutive pair of pulses substantially constant, and transmitting said modulated pulses.

6. In a radio frequency system, the steps of alternately producing radio frequency carrier pulses of two different frequencies, and impressing at least two different types of modulation on said carrier pulses in accordance with corresponding modulating signals.

7. In a radio frequency transmission system, the steps of alternately producing radio frequency carrier pulses of two different frequencies, modulating the frequency of said carrier pulses in accordance with the amplitude of one modulating signal while maintaining a substantially constant pulse time proportion between each consecutive pair of pulses, modulating the widths of the alternate carrier pulses in accordance with the amplitude of a second modulating signal, such that opposite and complementary changes in pulse width are produced in each consecutive pair of pulses, while maintaining a substantially constant pulse frequency, and transmitting said modulated pulses.

8. In a radio frequency system, the combination of means for alternately producing radio frequency carrier signals of different frequencies in the form of consecutive pulses of given time duration, and means for modifying the time durations of said carrier pulses in accordance with a modulating signal, while maintaining the total time duration of each consecutive pair of pulses substantially constant.

9. In a radio frequency system, the combination of means for generating two radio frequency carrier signals of different frequencies, means for alternately suppressing first one and then the other of said carriers to produce alternate carrier pulses of different frequencies, means for changing the widths of alternate of said carrier pulses in accordance with the amplitude of a modulating signal, and means for changing the widths of the intervening carrier pulses between said alternate pulses in inverse relation to the amplitude of said modulating signal, whereby opposite, complementary changes in pulse width are produced in each consecutive pair of pulses, and the total pulse width of each consecutive pair of pulses is maintained substantially constant.

10. In a radio frequency system, the combination of means for generating two radio frequency carrier signals of different frequencies, an electrical output circuit connected to receive inputs

from said generating means, means for rendering said electrical output circuit alternately responsive to said carrier signals whereby alternate carrier pulses of said different frequencies are produced, and means for controlling said last named means in accordance with a modulating signal such that the widths of said pulses are modulated in accordance with said modulating signal.

10. 11. In a radio frequency system, the combination of means for generating two radio frequency carrier signals of different frequencies, an electrical output circuit, a pair of electronic tubes connected to be responsive to said respective carrier signals and to supply signals of said different frequencies to said electrical output circuit, multivibrator means connected to supply blocking signals alternately to said tubes so that alternate carrier pulses of said different frequencies are fed to said electrical output circuit, and means for applying a modulating signal to said multivibrator means to cause the widths of the pulses therefrom to vary in accordance with the amplitude of said modulating signal while maintaining the total width of each consecutive pair of pulses substantially constant.

12. In a radio frequency system, the combination of means for generating two radio frequency carrier signals of different frequencies, an electrical circuit resonant at one of said frequencies, electrical means for changing the electrical constants in said electrical circuit to render it resonant at the other of said frequencies, electrical control means for rendering said electrical means alternately effective and ineffective to change the electrical constants in said electrical circuit, thereby rendering said electrical circuit resonant alternately at said different frequencies and producing alternate carrier pulses of said different frequencies, and means for supplying a modulating signal to said electrical control means to effect modulation of the widths of said carrier pulses in accordance with the magnitude of said modulating signal while maintaining the total pulse width for each consecutive pair of carrier pulses substantially constant.

13. In a radio frequency system, the combination of means for alternately producing radio frequency carrier pulses of different frequencies, means for modifying the widths of said carrier pulses in accordance with a modulating signal, while maintaining a substantially constant pulse frequency, and means for modifying the pulse frequency in accordance with a second modulating signal, while maintaining a substantially constant pulse time proportion between each consecutive pair of pulses.

14. In a radio frequency system, the combination of means for generating two radio frequency carrier signals of different frequencies, an electrical output circuit, a pair of electronic tubes connected to be responsive to said respective carrier signals and to supply signals of said different frequencies to said electrical output circuit, multivibrator means connected to supply blocking signals alternately to said tubes so that alternate carrier pulses of said different frequencies are fed to said electrical output circuit, means for applying a modulating signal to said multivibrator means to cause the widths of the pulses therefrom to vary in accordance with the amplitude of said modulating signal while maintaining the total width of each consecutive pair of pulses

substantially constant, and means for modulating the pulse rate of said multivibrator means in accordance with a second modulating signal.

15. In an electrical system, the combination of an auxiliary electrical element connected in said system, uni-directional conducting means connected in series with said element, and means for supplying one signal to said uni-directional conducting element to render it conducting and to connect said element to the system and for supplying another signal to said uni-directional con-

ducting means to render it nonconducting and to disconnect said element from the system.
